ELECTRIC HAIR DRYER NOZZLE

Eli Orsoff, Selden, N.Y., assignor to Continental
Hair Products, Inc., Edison, N.J.

Filed Aug. 30, 1973, Ser. No. 393,261

Term of patent 14 years

Int. Cl. D28—03

U.S. Cl. D86—10 F

FIG. 1

FIG. 2

FIG. 4

FIG. 3

FIG. 5

FIG. 1 is a perspective view of an electric hair dryer nozzle showing my new design;

FIG. 2 is a top plan view thereof;

FIG. 3 is a front end elevational view thereof;

FIG. 4 is a left side elevational view thereof; and

FIG. 5 is a rear end elevational view thereof.

I claim:

The ornamental design for an electric hair dryer nozzle, substantially as shown.
